DESIGN FOR A HOIST

Ola L. Berby, Duluth, Minn., assignor to Clyde
Iron Works, Duluth, Minn., a corporation of Maine

Application March 28, 1940, Serial No. 91,295

Term of patent 3½ years

To all whom it may concern:

Be it known that I, Ola L. Berby, a citizen of the United States, residing at Duluth, county of St. Louis, and State of Minnesota, have invented a new, original, and ornamental Design for a Hoist, of which the following is a specification, reference being had to the accompanying drawings forming part thereof.

I claim:

The ornamental design for a hoist, as shown.

OLA L. BERBY.
